(57) **CLAIM**

We claim the ornamental design for a combined electrical box cable management and support clip bracket, as shown and described.

DESCRIPTION

FIG. 1 is a perspective view of a combined electrical box cable management and support clip bracket showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

FIGS. 1-7 are various views of a combined electrical junction box cable management and support clip bracket in accordance with the present design. The cable management and support clip brackets provide pass through openings for cables being connected to an electrical junction box in an in-wall electrical power wiring system and optionally also provide far-side support for the electrical junction box.
